(57) **CLAIM**

I claim the ornamental design for a table, as shown and described.

DESCRIPTION

FIG. 1 is a perspective view of a table of my design.

FIG. 2 is a left side view of the table of FIG. 1, with the right side being a mirror image.

FIG. 3 is a front elevational view of the table of FIG. 1, with the rear elevational view being identical.

FIG. 4 is a top view of the table of FIG. 1; and,

FIG. 5 is a bottom view of the table of FIG. 1.
